DEMOUNTABLE BODY

Benjamin F. Fitch, Greenwich, Conn., assignor to
 Motor Terminals Company, New York, N. Y., a
 corporation of Delaware

Application May 18, 1933, Serial No. 671,717

7 Claims. (Cl. 220—1.5)

Systems of transferring freight employing demountable truck bodies, which may be lifted with their loads from a highway truck and deposited on a flat car for rail transportation, and 5 at the end of the rail haul placed on another truck for delivery to destination, are in effective use in various districts. Such system has been found very beneficial, as it avoids the delay and other disadvantages of breaking bulk and re- 10 packing at each end of the rail haul, inherent in the old box-car method of transportation, and likewise materially reduces the expense over that of continuous inter-city highway trucking.

To enable convenient loading and unloading of 15 the bodies, they must have end doors, and, as the body is likely to be mounted on the truck either end foremost, such doors must be provided at each end of the body. These are in addition to the side doors, which are needed on each side 20 of the body for convenient loading and unloading according to circumstances.

For the most economical handling on the trucks, and by the transfer cranes, the bodies must be as light as practicable, but, on the other 25 hand, provision must be made for resisting the strains to which the bodies are subjected in rail transportation. These strains occur particularly at the ends of the body and are caused by the impact of the load against the end doors, due to 30 the tugging and buffing stresses in starting and stopping the car. In a long train, where the engineer must take up slack and start the train with a jerk, this impact becomes very pronounced.

Double doors on each end of the body, pivotally 35 carried adjacent their outer edges, are desirable to allow a wide loading and unloading opening, but such double doors, due to the impact of the load, are liable in the rail transportation to become distorted or sprung. Moreover, as it has 40 been customary to hinge the doors to the door jamb, the impact against the doors is transmitted to the jamb, resulting in its distortion, which prevents a tight seating of the doors, and cannot be remedied by substituting new doors at the 45 job, but requires discarding the whole body until it can be taken to a proper plant for repair.

The present invention is designed to avoid the difficulties mentioned, which I accomplish by two changes in the established constructions, namely:

50 In the first place, I carry the hinge straps of the doors beyond the outer edges of the doors and beyond the jambs, clear to the sides of the body, and I secure the mating members of these hinge straps directly to the corner of the body, where they are effectively held by the side plates

of the body. In other words, that portion of the impact on the doors, which was formerly transmitted to the door jamb is now transmitted to the body sides, where it is effectively resisted by the side plates under tension.

5 The second change I make is to provide tie rods leading from the central region of the body and just above the doors to the sides of the car. The meeting edges of the doors are locked by bolts in the mid-region of the body end which engage the 10 floor frame and the end wall above the doors. The floor frame is sufficiently rigid to effectively resist the strain on the doors transmitted by the lower bolt. With my improvement at the upper 15 end, the tie rods in tension resist the strain on the upper bolt.

The sides of the body are provided with vertical 20 straps reinforcing the sides and terminating in hooks for the attachment of load lifting devices, and the lifting stress is transmitted to the floor 25 frame by these straps and also by a pair of inclined reinforcing bars leading downwardly from opposite sides of each hook strap to the floor frame. All of these straps are riveted to the body 30 sides and effectively transmit the lifting stress to the floor frame and also act to reinforce the sides. Now I secure the inner ends of the tie rods 35 above mentioned to the sides directly opposite the hook straps, so that the pulling stress on the tie rod, due to the upper door bolt pressing outwardly by impact of the load against the doors, is transmitted to regions of the body sides effectively braced by the diagonal side straps, one of which acts as a strut and the other a tension member.

By the means described, I am enabled to resist the internal impact against both the inner and outer portions of the end doors. The hinge straps are carried clear across the faces of the door and by being made in the form of load 40 resisting beams suitably webbed, as for instance, being channel-shaped in cross-section, effectively brace the doors against intermediate distortion.

45 My invention comprising a demountable body having the above outlined features for preventing end distortion due to internal impact, is illustrated in a preferred form in the drawings hereof, and is hereinafter more fully described in connection with such drawings.

50 In the drawings, Fig. 1 is a side elevation of a railway flat car on which one of my demountable bodies has been placed; Fig. 2 is an end view of such body; Fig. 3 is a longitudinal central section of a portion of the body adjacent one end 55

on a larger scale than Fig. 2; Fig. 4 is a transverse section through a portion of the body and as indicated by the line 4-4 on Fig. 3; Fig. 5 is a detail of the mounting of the fixed hinged member at the corner of the body, being a horizontal section on the line 5-5 on Fig. 2; Fig. 6 is a horizontal section through the upper portion of the body as indicated by the line 6-6 on Fig. 3; Fig. 7 is a detail on a larger scale of the hinge strap in elevation; Fig. 8 is a cross-section of a hinge strap, as indicated by the line 8-8 in Fig. 7.

Referring to Fig. 1, A indicates a railway flat car having upstanding projections *a*, and B indicates one of my demountable bodies adapted to seat on the car and be positioned by the projections *a*. The body is shown as having intermediate located side doors *b*. Secured to the side wall, between the side doorway and the ends of the body, are vertical straps *b*¹, riveted to the side wall and terminating at their upper ends in hooks *b*², which may be engaged to suitable hoist mechanism. On opposite sides of each strap *b*¹ are straps *b*³, also riveted to the side of the body and leading downwardly from points adjacent the strap *b*¹ at the eaves to points at the base a considerable distance therefrom, thus distributing the lifting strains well over the base of the body. These side straps appear in cross-section in Fig. 6, which shows them riveted to the sheet metal wall *b*⁴ of the body side.

The construction at the two ends of the body is identical, though only one end is shown in detail. The end wall comprises vertical plates *b*⁵, adjacent the edges, a top cross-plate *b*⁶, and a door jamb *b*⁷, the latter being preferably of Z-bar cross-section and connected to the side and top plates and to the base frame, designated *b*⁸. This base frame is made of suitable structural shapes and, as shown, bounded by channel beams. The edge plates *b*⁵ are connected at their outer edges with the body sides *b*⁴ by vertical angle bars *b*⁹, and the side and end plates and angle bars are all effectively secured to the floor frame.

The body is provided with a suitable roof *b*¹⁰ braced by cross beams leading from one side of the body to the other, one of which cross beams *b*¹¹ is shown in Fig. 3 as located between the hook straps *b*¹ and serves to brace the body transversely in this region. The construction so far described is one I have developed for freight transportation and is not of itself claimed in this application.

The doors *C*, which seat in the door jamb *b*⁷ at the end of the body may themselves be of any suitable construction adapted to make a snug connection with the door jamb and with each other at the meeting edge. These doors are shown in Fig. 4 as comprising two wooden panels *c* and *c*¹, offset from each other to provide rabbets at the opposite edges, and the panels are faced on their outer sides with sheet metal which projects around the ends and into the interior. Such construction is shown and claimed in my copending application Serial No. 649,193, filed December 65 28, 1932.

One of the doors has means at the meeting edge overlapping the other door, and providing for carrying upright locking bolts to engage the floor frame and the body above the door. I may provide for this purpose a hollow post *D*, secured to one of the doors and overlapping the other, as shown in Fig. 4, and as shown and claimed in my copending application Serial No. 625,977, filed July 29, 1932. This hollow post carries a pair of vertical bolts *d* and *d*¹, operated by a lever *d*²

and link *d*³, whereby the bolts may be drawn together to clear the door jamb above and below, or be extended, as in Fig. 3, to lock the doors.

I have referred to the doors as being mounted on hinges near their outer edges. The hinge axis, however, is not at the door edge, nor is the stationary hinge member secured to the door jamb. On the contrary, the hinge straps which are secured to the doors, extend across the end walls clear to the side of the body, and the stationary hinge members are located at the corners of the body.

As illustrated in Figs. 2, 4 and 5, brackets *10* are located at each corner of the body, these brackets embracing both outer faces of the corner angle beam *b*⁹ of the body, and securely riveted thereto by rivets *11*. The brackets carry upwardly extending stationary pintles *12*. The hinge straps which cooperate with these pintles are designated *15*. They extend across the end walls *b*⁵ and clear across the faces of the doors and are effectively secured to the doors at several points, as by means of bolts *16*, Figs. 2, 4 and 7, which extend through the door, these bolts passing preferably through elongated openings in the straps to enable the door to be accurately fitted to the strap so as to make a snug connection with the door jamb.

The hinge straps *15* are webbed to give them proper stiffness. They are preferably channel 30 beams, as shown in Figs. 7 and 8. I prefer to provide more than two of these strap hinges for each door, three being shown in Fig. 2, not only to make an effective hinge support, but to provide the further function of effectively bracing 35 the door.

The hinge straps *15* carry part of the internal thrust against the doors directly to the hinge brackets, which are secured to the rigid corners of the body and thus transmit the stress to the 40 side plates *b*⁴ in tension. The rest of the thrust is transmitted by the bottom bolt *d* to the floor frame, which is very rigid, and by the top bolt to the top wall *b*⁶ of the body end, which is braced to resist this thrust, as about to be de- 45 scribed.

The top wall is braced by an angle beam *b*¹² on its inside and by a flanged member *b*¹³ on the outside, which acts also as a draining gutter. This member may provide an upper drain be- 50 tween an outwardly inclined part of the member and the wall *b*⁶ and a lower drain immediately above the door, which latter may be overhung by a weather protecting flanged member *c*³, as shown in Fig. 3. These protecting features are 55 set out in my copending application 625,977, already mentioned, though the gutter member is of interest here on account of its characteristic of stiffening the lower edge of the top end wall. The end wall is still further braced in this in- 60 vention by diagonal tie bars *20*, which are riveted to the transverse beam *b*¹² and to a gusset *21*, also riveted to that beam, adjacent the trans- 65 verse center of the body just above the doorway. Tie bars lead diagonally outwardly to the sides 65 of the body and are riveted to said sides directly opposite the hook straps *b*¹, preferably the same rivets passing through the tie bar, the body side *b*⁴, and the hook strap, as illustrated in Fig. 6. A convenient way of making the tie bar is to 70 provide a flat metal strap twisted on itself 90°, as shown in this figure.

As the region where the outer ends of the tie bars are anchored is not only opposite the hook strap *b*¹ but adjacent the tops of the diagonal 75

braces b^3 , it will be seen that the brace b^3 nearest the end of the body forms a strut and the other brace b^3 a tie effectively anchoring the end of the tie bar 20. Accordingly, the outward stress, due 5 to the impact of the load against the doors, delivered by the bolt d^1 to the body frame above the doors, is effectively resisted, not only by the bracing b^{12} and b^{13} , but especially by these ties, which lead directly from the region adjacent the 10 locking bolt to the sides of the body.

It will be seen from the description given that the impact of the load against the doors is taken entirely off of the door jamb, and this takes care of the greatest difficulty, as the shifting movement 15 is greatest in the body some distance inwardly from the side walls, experience having demonstrated that there is little difficulty immediately adjacent such side edges. By mounting the hinges entirely independent of the door 20 jambs, I believe the latter of troublesome distortion, which has heretofore resulted, and which has caused leakage and required the discontinuance of the body until repaired.

I claim:

25 1. A demountable body having an end wall with a door jamb therein, doors adapted to seat in the door jamb, means for locking the doors to the floor frame of the body and to the end wall above the door jamb and adjacent the center line 30 of the end wall, and diagonal ties in the clear space within the body higher than the door opening adjacent the point where the end doors are locked to the end wall and leading from the central region of the end wall to the sides.

35 2. The combination of a demountable body having an end wall with a doorway in it materially narrower than the body and, which leaves wall portions between the outer edges of the doorway and the body sides, a pair of doors adapted 40 to seat in the doorway hinges carried at the end corners of the body having reinforcing straps leading across the end walls and secured to the doors, and means for locking the doors to the body adjacent the inner edges of the doors, and 45 a tension brace within the body for the end wall above the doors leading from the central region of the end wall to each of the sides.

3. A demountable body having side walls and 50 end walls, a door-way in the end wall narrower than the body, a pair of doors in the doorway, hinge straps horizontally webbed to stiffen them and extending substantially across the doors and effectively secured to the outer faces of the doors, said straps extending freely across the end wall 55 between the doors and sides of the body to transmit any strains directed to the doors directly to the side walls, brackets at the corners of the body, and hinge pins connecting the brackets with the straps and means for transmitting strains 60 from the inner portions of the doors through tension means to the side walls.

4. A demountable body having side and end 65 walls, a floor frame and a roof, straps secured to the outer face of the sides leading above the eaves and having provision at their upper ends for the attachment of a lifting mechanism, a doorway in the end of the body narrower than

the width of the body, doors in the doorway, hinge straps extending substantially across the outer face of the doors and thence across the end walls at the sides of the doors, means for pivoting the hinge straps to the body adjacent the corners of the body, means for locking the inner edges of the doors to the floor frame and to the end wall above the doors, and ties within the body connecting the central region of the end wall above the doors with the sides of the 10 body opposite the straps.

5. A demountable automobile body having an end wall with a doorway in it terminating below the top of the end wall, a pair of ties on the inside of the body each anchored at one end to a 15 common member which in turn is fastened to the end wall adjacent the transverse center and each anchored at their other ends to the sides respectively, a door adapted when closed to extend transversely of the body and have a free 20 edge adjacent the transverse center, and means for bolting said door to the body end adjacent the central anchorage of the ties whereby strains set up in the door may be transmitted through 25 said ties to the body side walls.

6. A demountable automobile body having an end wall with a doorway in it terminating below the top of the end wall, a pair of ties on the inside of the body each anchored at one end to the end wall adjacent the transverse center and each 30 anchored at their other ends to the sides respectively, overhead strut means transversely bracing the sides substantially at the regions in which said other ends of the ties are anchored, a door adapted when closed to extend transversely of 35 the body and have a free edge adjacent the transverse center, and means for bolting said door to the body end adjacent the central anchorage of the ties, whereby strains set up in the door may be transmitted through 40 said ties to transversely braced portions of the body side walls.

7. In a demountable body having side walls and a roof, a doorway including a door frame in one end of the body, an outwardly movable door mounted on the body and having a free edge arranged to close adjacent the upper part of the frame, locking means for securing the door to the frame above the door centrally of the body, oppositely disposed bracing structures for the side walls extending adjacent the side walls and joined 50 thereto, an overhead cross bracing means forming a strut between the upper portions of the side walls substantially in the transverse plane of the bracing structures and operatively joined to respective said structures, and diagonal overhead tension members connected to both sides of the body in the regions thereof where the bracing structures are operatively joined by the strut, said tension members being connected to the door frame above the door in the region of the locking means of the door, whereby strains on the door tending to break open the locking means will be effectively resisted by rigid portions of the body independently of the frame.
